SET OF BRACKETS FOR PAPER TOWEL PACKAGES OR THE LIKE

William A. Blake, 8757 NE. Prescott St.,
Portland, Oreg. 97220

Filed Jan. 28, 1974, Ser. No. 436,992

Term of patent 14 years

Int. Cl. D8—08

U.S. Cl. D8—233

FIG. 1

FIG. 2

FIG. 3

FIG. 4

FIG. 5

FIG. 6

FIG. 1 is a perspective view of the bracket as viewed toward the front and left end showing in phantom lines a rectangular package inserted therein, such phantom lines being for illustrative purposes only;

FIG. 2 is a left end elevation;

FIG. 3 is a right end elevation;

FIG. 4 is a top view of the left-hand bracket section of FIG. 1;

FIG. 5 is a back elevational view of the left-hand bracket section of FIG. 1; and

FIG. 6 is a front elevational view of the left-hand bracket section of FIG. 1.

I claim:

The ornamental design for a set of brackets for paper towel packages or the like, as shown and described.
